UNITED STATES PATENT OFFICE.

JAMES S. THOMPSON, OF PELHAM, NEW YORK.

MANUFACTURE OF BRAKE SHOES.

Application filed July 20, 1923. Serial No. 652,789.

To all whom it may concern:

Be it known that I, JAMES S. THOMPSON, a citizen of the United States, residing at Pelham, in the county of Westchester and State of New York, have invented certain new and useful Improvements in the Manufacture of Brake Shoes, of which the following is a specification.

This invention relates to the manufacture of brake shoes, and it has for its object to facilitate the operation of setting up the mold for casting the brake shoe, to reduce the time and labor involved and lessen the cost of manufacture.

More specifically, my invention has for its object to assemble in a unit the parts which are to be inserted in the mold cavity for embedment in the shoe casting, and which usually comprise a reinforcing back, a steel lug and a core for forming the opening in the lug, whereby the unit can be handled easily and quickly and without damage thereto or to the mold.

And a further object of the invention is to tie the reinforcing back, the steel lug and the core for forming the opening in the lug together in a compact unit so that it can be easily handled without disarranging its parts, whereby it can be inserted bodily in the mold cavity and supported or suspended therein while the mold is being closed and during the casting operation.

In the accompanying drawings, I have shown two selected embodiments of the invention, in which the difference resides in the shape of the core, and referring thereto—

Fig. 1 is a perspective view of an assembly unit for use in a mold such as that described in my co-pending applications, Serial Nos. 652,771 and 652,772 filed July 20, 1923.

Fig. 2 is also a perspective view of an assembly unit for use in a mold such as that described in my co-pending applications Serial Nos. 652,775 and 652,776 filed July 20, 1923.

Fig. 3 is a transverse sectional view on the line 3—3 of Fig. 1.

Referring to the drawings, 5 is the reinforcing back, 6 the steel lug and 7 the core for forming the opening in the lug in casting the shoe. These parts are assembled in the usual way, the hooked ends 6', 6' of the lug being engaged with the recessed sides 5' of the back, and the core being inserted

in the lug and extending lengthwise of the back on both sides of the lug. In Fig. 1 I have shown a core of a particular form for use in a mold having a cavity therein shaped to receive this core, and in Fig. 2 I have shown another form of core adapted to fit in a mold having a cavity made to receive it. I do not restrict myself to the use of a back or a lug or a core of the kind illustrated in the drawings, for it will be obvious that my invention is adaptable for embodiment with backs, lugs and cores of many different kinds, and I wish it to be understood that my invention is not limited or restricted by the disclosure of the selected form herein.

My invention consists in tying the parts together in an assembly so that they can be handled and inserted in the mold as a unit, whereby the handling operation is simplified and facilitated, the danger of damaging the core is practically eliminated, and the liability of the parts becoming disarranged in the mold is avoided. I accomplish this in a very simple manner by providing wire ties 8, 8, which are passed around the core, preferably on each side of the lug, and are engaged with the back by twisting the ends together at 8'. I find it convenient to make the twist beneath the back, but it can be otherwise disposed if found more desirable. The core fits snugly in the lug between the top of the lug and the top of the reinforcing back, the sides of the lug engage the side edges of the reinforcing back to hold the back in proper relation to the lug, and the wire ties secure the back and the core together in a rigid manner to assemble all the parts in the form of a single unit.

My invention makes it possible for the back, the lug and the core to be assembled by relatively unskilled workmen and delivered to the molder for insertion in the mold cavity, whereby the operation of setting up the mold is facilitated and expedited. The assembly units can be made up in quantities and kept in stock for use as required. By providing the unit I am enabled to reduce the cost of manufacturing brake shoes, and at the same time to facilitate the operation and insure proper positioning of the parts in the mold cavity of the mold.

I am aware that changes in the form, construction and arrangement of parts may be made in my invention to adapt it for different conditions, without departing

from the spirit or sacrificing the advantages thereof, and I consider myself entitled to make all such changes as fairly fall within the scope of the following claims.

5. I claim:

1. In the manufacture of brake shoes, an assembly unit of parts to be inserted in the mold cavity of the brake shoe mold, and comprising a reinforcing back, a core for forming the opening in the attaching lug of the shoe, and means for fastening the back and the core together.
10. 2. In the manufacture of brake shoes, an assembly unit of parts to be inserted in the mold cavity of the brake shoe mold, and comprising a reinforcing back, an attaching lug, a core for forming the opening in the lug, and means for fastening the back and the core together.
15. 3. In the manufacture of brake shoes, an assembly unit of parts to be inserted in the mold cavity of the brake shoe mold, and comprising a reinforcing back, a steel lug

engaged with said back, a core for forming the opening in the lug and interposed between the lug and the back, and means for fastening the back and the core together.

4. In the manufacture of brake shoes, an assembly unit of parts to be inserted in the mold cavity of the brake shoe mold, and comprising a reinforcing back, a core for forming the opening in the attaching lug of the shoe, and a wire fastened around the core and the back for securing said parts together.

5. In the manufacture of brake shoes, an assembly unit of parts to be inserted in the mold cavity of the brake shoe mold, and comprising a reinforcing back, a steel lug engaged with said back, a core for forming the opening in said lug, and wires fastened around the core and the back on opposite sides of said lug for securing the back and core together.

JAMES S. THOMPSON.
